(57) **CLAIM**

The ornamental design for a utility knife, as shown and described.

DESCRIPTION

FIG. 1 is a front elevation view of a utility knife, showing my new design;

FIG. 2 is a side elevation view thereof;

FIG. 3 is a perspective view thereof;

FIG. 4 is a rear elevation view thereof; and

FIG. 5 is a bottom plan view thereof; and,

FIG. 6 is a bottom plan view of the utility knife of FIG. 1. The broken lines illustrate portions of the utility knife that form no part of the claimed design.
